ATTORNEY

UNITED STATES PATENT OFFICE

159,194

FLOWER HOLDER OR SIMILAR ARTICLE

Daniel Eisenberg, Plainfield, N. J., assignor to Spaulding China Co., Inc., New York, N. Y., a corporation of New York

Application December 30, 1948, Serial No. 150,449

Term of patent 3½ years

(Cl. D35—3)

To all whom it may concern:

Be it known that I, Daniel Eisenberg, a citizen of the United States, residing at Plainfield, in the county of Union and State of New Jersey, have invented a new, original, and ornamental Design for a Flower Holder or Similar Article, of which the following is a specification, reference being had to the accompanying drawing, forming part thereof.

In the drawing

Fig. 1 is a front view of a flower holder or similar article, showing my new design;

Fig. 2 is a side view thereof;

Fig. 3 is a rear view thereof; and

Fig. 4 is a top view.

I claim:

The ornamental design for a flower holder or similar article, substantially as shown.

DANIEL EISENBERG.
